UNITED STATES PATENT OFFICE

IRENE C. ROBY, OF CHICAGO, ILLINOIS, ASSIGNOR OF TWENTY-FIVE PER CENT TO
CLARENCE E. WILLIAMS, OF CHICAGO, ILLINOIS

DESIGN FOR A BOOK RACK OR SIMILAR ARTICLE

Application filed July 17, 1930. Serial No. 36,379. Term of patent 14 years.

To all whom it may concern:

Be it known that I, IRENE C. ROBY, a citizen of the United States, residing at Chicago, in the county of Cook and State of Illinois, have invented a new, original, and ornamental Design for a Book Rack or Similar Article, of which the following is a specification, reference being had to the accompanying drawing, forming part thereof.

The figure is a perspective view of a book rack, showing my new design.

I claim:

The ornamental design for a book rack or similar article, as shown.

IRENE C. ROBY.
